DISPENSER CABINET FOR ROLLED SHEET MATERIALS

Harold O. Wagner, Sheffield Lake, and Manuel S. Ziskin,
Mayfield Heights, Ohio, assignors to American Trading
and Production Corporation, Baltimore, Md.

Filed Apr. 27, 1966, Ser. No. 2,043

Term of patent 14 years

(Cl. D52--2)

Fig. 1

Fig. 2

Fig. 3

Fig. 4

Fig. 5

FIG. 1 is a top plan view of a dispenser cabinet for rolled sheet materials, embodying our new design;

FIG. 2 is a front elevational view of the dispenser cabinet;

FIG. 3 is a rear elevational view of the dispenser cabinet;

FIG. 4 is a side elevational view of the dispenser cabinet, as viewed from the left side of FIG. 2, and

FIG. 5 is a bottom plan view of the dispenser cabinet.

The undisclosed side of the dispenser cabinet is substantially the same in appearance as the side shown.

We claim:

The ornamental design for a dispenser cabinet for rolled sheet materials, substantially as shown and described.
